INVENTOR.

James Barnett

UNITED STATES PATENT OFFICE.

JAMES BARNETT, OF LOUISVILLE, KENTUCKY.

CORE-STAND.

SPECIFICATION forming part of Letters Patent No. 359,660, dated March 22, 1867.

Application filed December 23, 1885. Serial No. 186,517. (No model.)

To all whom it may concern:

Be it known that I, JAMES BARNETT, a citizen of the United States, residing at Louisville, in the county of Jefferson and State of Kentucky, have invented certain new and useful Improvements in Core-Stands, of which the following is a full, clear, and exact description, reference being had to the accompanying drawings, forming part of this specification.

10 My invention relates to new and useful improvements in stands for forming the cores used in molds for casting iron pipes; and it consists, generally, of a box cast or fitted in the core-stand and containing an adjustable and removable pillow-block for the journal of the core-bar to rest in, with screws for adjusting and firmly setting the pillow-block, and also of a detachable seat for an adjustable core-board, with pins for firmly holding the seat 15 on the core-stand and allowing it to be readily detached therefrom, and having slotted bolt-openings, so that the core-board may be readily moved on the seat, and then be adjusted and securely fastened by means of bolts.

20 This construction is clearly shown in the accompanying drawings, which are illustrative 25 of my invention, and in which—

Figure 1 is a perspective view of my improved core-stand. Fig. 2 is an enlarged like 30 view of one end of the same, the other end being similar. Fig. 3 is a vertical transverse sectional view of the box and pillow-block through the line $x\ x$, Fig. 2. Fig. 4 is a perspective view of a pillow-block with two journal-seats. Fig. 5 is a perspective view of the 35 core-board seat, bottom side up, to show the pins beneath, and Fig. 6 is a vertical longitudinal sectional view of the core-board seat through the line $y\ y$, Fig. 5, but with the top 40 side up.

In the different figures like letters indicate like parts.

B is an adjustable core-board. C is a core-bar. D is a core, shown in dotted lines on the 45 core-bar C. E is an adjustable and removable pillow-block with a single journal-seat. E' is a like pillow-block with two journal-seats, of which the one farthest from the core-board B may be used as a rest for the core-bar C when 50 receiving the material (usually hay and clay) for forming the core, while that nearest the

core-board B corresponds with the single journal-seat in the pillow-block E, and is used as a rest for the core-bar C while the core is being formed. F is a crank to turn the core-bar. G are screw-bolts passing through the bottom of the box I, for elevating and depressing the pillow-block. H are screw-bolts passing through the side of the box I, for securing the pillow-block in position. I is a box in the 55 core-stand A to receive the pillow-block. J are the legs of the core-stand A. K is the beveled forming or shaping edge of the core-board B. L are journal-seats in the pillow-block. M are the core-stand feet. N is the seat for 60 the core-board B. O are bolts to secure the core-board B to the seat N. P is a depression in the box I, so as to allow the core-bar C to revolve when the pillow-block is set low in the box I. Q are pins to hold the seat N in position on the core-stand A. R are stops in the seat N, through which the bolts O pass, the lower part of the slots being enlarged to accommodate the bolt-heads.

In practice with my invention, when the 75 pillow-block and the core-board have been adjusted, by means of the screws and bolts, with regard to the desired size and weight of pipe 80 to be made, and so as to bring the core material in contact with the core-board, the core-bar carrying the material for the core is revolved, when the shaping-edge of the core-board will form the material into a cylindrical core around the core-bar, and as fresh material is added to the core the same action of 85 revolving and shaping it is continued until the core is completed. As the journal-seat in the pillow-block wears away the block is elevated to the proper position by means of the screws G, and when the journal-seat is too much 90 worn for further use the pillow-block is readily taken out and replaced with a new one. When it is necessary to use a wider or narrower core-board, the core-board in use, together with the core-board seat attached to it, 95 may be at once lifted from the core-stand and immediately replaced by another core-board and seat. By these means cores of different diameters may be readily and easily made on the same core-stand.

100 Among the advantages of my invention are, that it is not attended with the breakages in-

cident and usual to the case where the core-board seat and journal-seat are made or contained in one piece; that as the journal-seat wears away from use the pillow-block may be 5 readily and easily adjusted so as to bring the core-bar into proper position to form the core, and when too much worn the pillow-block may be speedily replaced with a serviceable one; that the core-board may not only be adjusted laterally to the core, but may be promptly changed for another, as may be necessary or required, and that great uniformity in size and weight of pipe is secured, and time, labor, and material are economized.

15 Having fully described my invention, what I claim as new, and desire to secure by Letters Patent, is—

1. A core-stand embracing, in combination, an adjustable and removable pillow-block, adjustable core-board, and detachable core-board 20 seat, substantially as described.

2. A core-stand embracing a detachable core-board seat, substantially as described.

3. A core-stand embracing an adjustable core-board, and a core-board seat detachable 25 from the core-stand and core-board, in combination, substantially as described.

Signed at Louisville, Kentucky, this 19th day of December, 1885.

JAMES BARNETT.
